In Great Britain July 19, 1947

Term of patent 3½ years

(Cl. D44—9)

To all whom it may concern:

Be it known that I, George McWilliams, a subject of the King of Great Britain and Northern Ireland, residing at Salford, in the county of Lancaster, England, have invented a new, original, and ornamental Design for a Double Saucer or the like, described in the specification filed September 16, 1947, Serial No. D-141,423, reference being had to the drawing accompanying said specification and forming part thereof, in which drawing,

Fig. 1 is a plan view of a double saucer or the like, showing my new design.

Fig. 2 is a section on the longitudinal center line 2—2 of the article shown in Fig. 1, and

Fig. 3 is an underside plan view of the same.

I claim:

The ornamental design for a double saucer or the like, as shown.

GEORGE McWILLIAMS.
